VAPOR ELECTRIC CONVERTER

Joseph Slepian, Pittsburgh, Pa., assignor to Westinghouse Electric & Manufacturing Company, East Pittsburgh, Pa., a corporation of Pennsylvania

Application July 16, 1935, Serial No. 31,591

5 Claims. (Cl. 175—363)

My invention relates to a vapor electric converter and particularly to an excitation system and a make-alive type converter.

In the application of make-alive type converters, it has been customary to use suitable auxiliary valves usually of the hot-cathode type to supply make-alive current from the main anode of the converter valve to the make-alive electrode. In application, these auxiliary valves are called upon to deliver relatively short current impulses of considerable magnitude. These relatively high current impulses have proven unexpectedly detrimental to the auxiliary valves so that the replacement of these auxiliary valves has proven a major item of upkeep expense for the converters.

It is, therefore, an object of my invention to provide a make-alive system utilizing auxiliary valves of the type which are sufficiently rugged to withstand the necessary current impulses, and thereby reduce the upkeep cost of such converters.

In the construction according to my invention, the heretofore usual hot-cathode auxiliary valves are replaced by a suitable vapor electric device of sufficient size and current capacity to supply the necessary make-alive current. These auxiliary valves may all be grouped in a single auxiliary converter. The make-alive electrodes are then energized by means of an auxiliary impulse transformer responsive to the current flow in the auxiliary valves.

Preferably, the auxiliary valves are directly connected to the anodes of the make-alive valves, but, if desired, they may be supplied with current from any suitable source.

Also, I have found that the auxiliary valves may conveniently be incorporated as auxiliary anodes, in the make-alive converters. When this is done, the auxiliary anode for any given valve is inserted in another make-alive valve, which is normally excited at the time when the anode of the valve being excited becomes positive. In this manner, the auxiliary valve will be in a tube which is excited at the instant it is desired to excite the next succeeding valve. Suitable grid control may be supplied for the auxiliary valves to delay the excitation of the make-alive electrode until the anode of the main valve being excited becomes sufficiently positive to guarantee striking of the conversion arc therein.

Other objects and advantages of my invention will be apparent from a detailed description when

taken in conjunction with the accompanying drawings, in which:

Figure 1 is a schematic illustration of a converter embodying my invention; and

Fig. 2 is a similar view of a modification showing the auxiliary anodes placed in the make-alive type valves.

The apparatus according to my invention comprises an alternating-current circuit 1 and a direct-current circuit 2 connected by means of a valve make-alive type converter 3 and a suitable transformer 4 for controlling the operation of the valves 5 of the converter 3. Each of the valves 5 of the converter 3 comprises a main anode 6 and a cathode 7 with a make-alive type electrode 8; that is, an electrode having a stem 9 of conducting material and a terminal 10 of semi-conducting material making positive and permanent contact with the cathode 7 under all normal operating conditions.

Connected in parallel with the anode 6 and cathode 7 of the main converter valve 5 is an auxiliary valve 15 for providing excitation current to the make-alive electrode 8. This auxiliary valve 15 is connected in series with the primary winding 16 of a suitable make-alive transformer 17, the secondary 18 of which is connected to the make-alive electrode 8 and to the cathode 7 of the main valve 5. Consequently, when current flows through the auxiliary valve 15, the current flow energizes the make-alive transformer 17 and supplies a current impulse to the make-alive electrode 7, which in turn creates a cathode spot in the make-alive valve 5, and permits the formation of a current-carrying arc 35 therein.

The auxiliary valves 15 for supplying current to the make-alive electrodes 7 are preferably placed in a constantly excited device, and, if desired, they may, as shown, all be placed in a single auxiliary vapor arc rectifier 20. The auxiliary valves 15 are preferably provided with a suitable resistor 21 and reactor 22 for controlling the current therethrough, said reactance 22 and resistance 21 being sufficient to cause the discontinuance of the auxiliary arc after the striking of the arc in the main converter valve 5.

Preferably, the auxiliary valves 15 are provided with suitable control grids 25, so that current will not be allowed to flow therein until such time as the potential of the main anode 6 is sufficiently positive to guarantee striking of the main arc when the cathode spot is created by the make-alive electrode 8. Also, this control grid 25 may be utilized for delaying the creation of the cath-

ode spot until any desired instant in the positive or normally conducting half cycle, whereby the voltage and current output of the converter 3 may be regulated.

5 Since the currents in the make-alive transformer 17 are unidirectional in character, there is a tendency for the cores 26 of the transformers 17 to become saturated. This may be overcome by special construction of the transformer core, 10 or by combining two or more make-alive transformers 17 on the same core and so adjusting the windings of the separate transformers 17 that the successive energization of these transformers reverses the residual flux in the transformer 15 core 26.

In the operation of the converter according to my invention, the device is put in operation by first exciting and then maintaining the excitation of the auxiliary rectifier 20. Then by the 20 application of potential to the transformer 4, positive potential will be applied to at least one of the main anodes 6 of the converter 3, which positive potential is also applied to the parallel connected auxiliary valve 15, and if the control grid 25 of this auxiliary valve is released, an arc will strike in the auxiliary valve 15 and the current flow through the valve 15 energizes the make-alive transformer 17 which produces a cathode spot in the corresponding main converter valve 5. Upon the pickup of the converter arc in this valve 5, the reactance 22 and resistance 21 in series with the auxiliary valve 15 concludes current flow therein and stops the current application to the make-alive electrode 8, so that 30 after the termination of the normal conducting arc therein, there will be no excitation until the main anode again becomes positive.

Control impulses may be supplied to the electrodes for the auxiliary valves 15 from any suitable source, such as a grid-control transformer 30. If desired, this transformer 30 may be provided with a phase shift in the form of an induction regulator 31, the primary 32 of which is connected to a suitable source of supply, such as the 45 alternating-current circuit 1, and the secondary 33 of which is connected to the primary of the control transformer 30.

In the modification according to Fig. 2, each of the main make-alive valves 35 is provided with 50 an auxiliary electrode 36 connected through the primary 37 of a suitable make-alive transformer to the anode 6 of the next succeeding valve 35. Consequently, when the anode 6 in the next succeeding valve 35 becomes positive, the auxiliary 55 anode 36 will strike to the cathode 7 of the preceding valve 35, which is still excited because of the flow of converter current therein. The flow of current to this auxiliary anode 36 energizes the secondary 38 of the make-alive transformer, and 60 supplies a current impulse to the make-alive electrode 8 which then creates a cathode spot and excites the succeeding valve 35. If desired, suitable control grids 41 may be applied to the auxiliary anodes 36 so that the cathode spot will not 65 be created before there is sufficient positive potential on the main anode 6 to permit pick-up of the current-carrying arc in the excited valve 35.

Any one of the make-alive transformers may 70 be provided with a suitable device such as an auxiliary valve 39 and switch 40 to procure an original current impulse to make-alive electrode when the device is being first energized.

To start the device in operation, the switch 40 75 is closed, then, when the anode 6 connected

thereto becomes positive, the valve 39 permits current flow in the primary 37 of the make-alive transformer and supplies current to the make-alive electrode 8 associated therewith and permits pick up of the arc in the make-alive valve 5, 35, after which the switch 40 is opened.

Once put in operation, the converter continues automatically and, as each succeeding valve becomes positive, the auxiliary anode therefor and associated with the preceding valve becomes operative and supplies current to the make-alive of the succeeding valve.

For purposes of illustration, I have shown specific embodiments of my invention; however, it will be apparent to those skilled in the art that 15 many changes may be made therein without departing from the true spirit of my invention or the scope of the appended claims.

I claim as my invention:

1. A vapor-electric converter comprising a plurality of valves connected for successive operation, each of said valves having a main anode and a cathode of vaporizable reconstructing material, a make-alive electrode in permanent contact with said cathode, and means for intermittently causing current flow in said make-alive electrode comprising an auxiliary anode in another of said valves and connected to the anode of the valve being excited and a transformer energized by current 25 flow to said auxiliary electrode. 30

2. A vapor-electric converter comprising a plurality of valves connected for successive operation, each of said valves having a main anode and a cathode of vaporizable reconstructing material, a make-alive electrode in permanent contact with said cathode, means for intermittently causing current flow in said make-alive electrode comprising an auxiliary anode in another of said valves and connected to the anode of the valve being excited and a transformer energized by current 35 flow to said auxiliary electrode, and means connected to one of said transformers for initiating 40 operation of said converter.

3. A vapor-electric converter comprising an evacuated valve chamber, an anode and a cathode in spaced relation in said chamber, a control electrode having a conducting stem and a tip of semi-conducting material in permanent contact with said cathode, an auxiliary anode connected to the first-mentioned anode, said auxiliary anode being 50 in a separate discharge device, said separate discharge devices being excited at the time the anode becomes positive, a transformer having a primary winding connected in series with said auxiliary anode and a secondary winding connected 55 between the conducting stem of the control electrode and said cathode.

4. A vapor-electric converter comprising an evacuated valve chamber, an anode and a cathode in spaced relation in said chamber, a control electrode having a conducting stem and a tip of semi-conducting material in permanent contact with said cathode, an auxiliary anode connected to the first-mentioned anode, said auxiliary anode being 60 in a separate discharge device, said separate discharge devices being excited at the time the anode becomes positive, a transformer having a primary winding connected in series with said auxiliary anode and a secondary winding connected between the conducting stem of the control electrode 70 and said cathode, a control grid associated with said auxiliary anode and means for impressing control potential thereon.

5. An electric conversion system comprising an alternating-current circuit, a direct-current cir- 75

cuit, a plurality of make-alive type valves for transferring energy between said circuits, transformer means for connecting said valves to both of said circuits, each of said valves comprising 5 two principal electrodes, a make-alive electrode cooperating with one of said principal electrodes to create a cathode spot thereon, said valves being so connected to said transformer that the valves are successively operative to transfer current between said circuit the potential across the suc-

ceeding valve normally becoming positive before the cessation of conduction in the last preceding valve and means for energizing the make-alive electrode of each succeeding valve comprising an auxiliary electrode in the preceding valve said auxiliary electrode being connected to the positive electrode of the succeeding valve and a transformer winding in said connection. 5

JOSEPH SLEPIAN. 10
